UNITED STATES PATENT OFFICE.

LOUIS McMURRAY, OF BALTIMORE, MARYLAND.

APPARATUS FOR CLEANING CORN OR OTHER GRAIN.

SPECIFICATION forming part of Letters Patent No. 391,482, dated October 23, 1888.

Application filed June 4, 1888. Serial No. 276,064. (No model.)

To all whom it may concern:

Be it known that I, LOUIS McMURRAY, of the city of Baltimore and State of Maryland, have invented a new and Improved Apparatus 5 for Cleaning Corn or other Grain and Packing the Same in Cans.

The following is a full description of my apparatus, illustrated by the accompanying drawings, of which—

10 Figure 1 is a perspective view of the apparatus, showing the revolving tub, revolving paddles, the stationary cleaners, a box of cans seated upon the inclined rack, and the mechanism which gives movement to the parts.

15 Fig. 2 is an upright side view of the apparatus, showing the tub provided with rollers and seated upon a track, and in dotted lines the shaft for revolving the tub. Fig. 3 is a top view of the apparatus, showing the tub, pin-

20 ions on the paddles and cleaners, rack, and shaft for rocking the rack; Fig. 4, a side view of box containing a series of cans with funnels in the openings at the top; Fig. 5, a top view of the same. Fig. 6 is an upright edge view

25 of one of the revolving paddles; Fig. 7, a side view of the same; Fig. 8, an edge view of one of the cleaners; Fig. 9, a side of the same. Fig. 10 is a sectional view of the tub with its rollers seated upon the track, and showing the

30 stirrers and cleaners within the tub; Fig. 11, an end view of the trip-wheel and its shaft.

My invention may be used for cleaning and packing any kind of grain, but is specially adapted for use in packing corn for market.

35 A A is a frame-work adapted to support the devices of the apparatus. Upon the upper part of this frame-work is journalled the shaft a' , provided with the pulley a'' , to which is imparted revolution by means of the belt a'' , 40 driven by a pulley on a driving-shaft. The cross-pieces a^4 a^5 of the frame-work serve to journal and support an upright shaft, a^6 . This shaft is provided at its upper end with the bevel-wheel a^7 , and receives its motion from

45 the pin a^8 on the end of shaft a' .

B is a revolving tub, to which the end of the revolving shaft a^6 is properly secured, and may be provided with rollers b' , running upon a circular track, b^2 . The cross-beams a^4 a^5 also

5 support and journal the upright revolving shafts b^3 , Figs. 1 and 10, which are provided on their upper ends with pinions b^4 , meshing with each other and receiving motion from a similar pinion, a^9 , on shaft a^6 , so that these shafts, alternating with each other, revolve in 55 reverse directions. The lower ends of these shafts project down into the revolving tub B, and may be flattened out or be provided with paddles, as shown at b^5 . As these paddles revolve, they act as stirrers or separators to agitate the corn or grain in the tub B. Supported also by the cross-beams a^4 a^5 are the cleaners b^6 , which are stationary and project down into the tub. The parts of the cleaners so projecting are usually made V-shaped, presenting the 65 apex of the V to the grain revolving with the tub, and their purpose is to catch the silk and husks of the corn and hold them.

D is a rack consisting of the side pieces, d' , joined together by the cross-bars d^2 . These 70 cross-bars are made of round iron of sufficient strength, and are arranged so they may turn or revolve. This rack-frame is pivoted near its upper end. A cross-shaft, d^3 , is journalled in the frame-work of the apparatus, revolved 75 by a belt running on the pulley d^4 . This cross-shaft is provided with one or more trip-wheels, d^5 , which operate upon projections d^6 on the rack-frame and trip the frame as they revolve. E is a box provided with a series of recesses 80 for holding the cans e' . In each of these cans a funnel is placed, as shown at e^2 . This box is placed upon the rack D at its upper end, and retained in place until the cans are charged by the latch e^3 . Around the tub B an iron 85 rim, b^7 , is secured for convenience in dumping the buckets of corn into the tub. A cup, as F, is usually placed near at hand. This cup will hold the required quantity of corn for each can.

90 The operation of the device is as follows: The corn, being first cut from the cob, is carried in buckets and dumped into the tub B. A box of cans provided with their respective funnels are placed upon the inclined rack and held there by the latch e^3 . The tub is revolved, as also the paddles b^3 , which stir up the corn without injuring it, while at the same time loosening the tassel, silk, and husks, which remain in the corn after it is removed from the 95 100

5 cob. As the tub revolves, these latter are caught and held by the cleaners b^6 . The operator then takes the cup F and dips the corn from the tub, which is poured into the funnels in the cans. When all are filled, the latch e^3 is released, and the box E , with its charge of cans, slowly descends the inclined rack, which being constantly tripped in its passage, the corn is well shaken down, and is entirely packed away in the can by the time it reaches the lower end of the rack. Another box is filled, and so on consecutively.

10 What I claim as my invention is—

1. In an apparatus for cleaning and pack-

15 ing grain, a revolving tub, in combination with a series of revolving stirrers and a series of stationary cleaners, substantially as set forth.

2. In an apparatus for cleaning and packing grain, a revolving tub provided with a series of revolving stirrers and a series of stationary cleaners, in combination with a packing device consisting of a rack for holding the cans and means for rocking the rack, substantially as described.

LOUIS McMURRAY.
